FIG. 4

LIQUID CRYSTAL DISPLAY DEVICE FOR IMPROVING COLOR WASHOUT EFFECT

BACKGROUND OF THE INVENTION

1. Field of the Invention

The present invention relates to a liquid crystal (LCD) display device for improving color washout effect, and more particularly, to an LCD device for improving color washout effect, caused by a side viewing angle, by modulating sub-pixel voltages through driving signals of scan lines.

2. Description of the Prior Art

Liquid Crystal Display (LCD) devices have many advantages, such as compact size, low power consumption, and low radiation. Therefore, the LCD devices have been widely applied to a mass of digital products, such as a laptop, a desktop and a personal digital assistance (PDA), and gradually replaced conventional Cathode Ray Tube (CRT) televisions to become the mainstream of consumer TV applications.

Compared with the conventional CRT device, the LCD devices tend to have brightness variation and contrast variation due to all kinds of viewing angle, and even have gray level inversion when the viewing angle is wide. Thus, a bunch of technologies, such as Multi-domain Vertical Alignment (MVA), In-Plane Switching (IPS), and etc, have been developed in industry to improve the LCD viewing angle problems. However, there still exists color washout effect and Gamma curve offset in the MVA LCD devices when people watch the screen from a large viewing angle.

One of driving approaches in the prior art, for solving the color washout effect, is dividing each pixels of the LCD into two sub-pixels. Each of sub-pixels is individually controlled by a Thin Film Transistor (TFT). Thus, by inputting two driving voltages with a subtle difference to two sub-pixels, liquid crystals of the two sub-pixels would have different inclined angles, and thereby improve the washout effect caused by a large viewing angle.

Further, as disclosed in US patent publication No. US20040001167A1, entitled "Liquid Crystal Display Device", an LCD device connects a storage capacitor of each sub-pixel to an external signal. After the TFT of each sub-pixel turns off, voltages on a counter electrode of the storage capacitors are disturbed by the external signals to diverge driving voltages of two sub-pixels, so as to improve the wash-out effect.

However, the aforementioned doings need not only an extra circuit for generating modulation signals of the storage capacitors, but extra layouts on the LCD panel for transmitting modulation signals of the storage capacitors. As a result, the aperture ratio of the LCD is decreased.

SUMMARY OF THE INVENTION

It is therefore an objective to provide a liquid crystal display (LCD) device for improving color washout effect.

The present invention discloses an LCD device for improving color washout effect. The LCD device includes a first data line, a first scan line, a second scan line, a third scan line, a pixel and a gate driving circuit. The second scan line is a next scan line of the first scan line. The third scan line is a next scan line of the second scan line. The pixel is formed at an intersection of the first data line and the first scan line and includes a first sub-pixel, and a second sub-pixel. The first sub-pixel includes a first liquid crystal capacitor, a first storage capacitor, and a first switch. The first liquid crystal capacitor has a first terminal and a second terminal electrically connected to

a common voltage. The first storage capacitor has a first terminal and a second terminal electrically connected to the second scan line. The first switch has a first terminal electrically connected to the first scan line, a second terminal electrically connected to the first terminal of the first liquid crystal capacitor and the first terminal of the first storage capacitor, and a control terminal electrically connected to the first scan line. The second sub-pixel includes a second liquid crystal capacitor, a second storage capacitor, and a second switch. The second liquid crystal capacitor has a first terminal and a second terminal electrically connected to the common voltage. The second storage capacitor has a first terminal and a second terminal electrically connected to the third scan line. The second switch has a first terminal electrically connected to the first data line, a second terminal electrically connected to the first terminal of the second liquid crystal capacitor and the first terminal of the second storage capacitor, and a control terminal electrically connected to the first scan line. The gate driving circuit is electrically connected to the first scan line, the second scan line and the third scan line, and used for generating driving signals of the first scan line, the second scan line and the third scan line in sequence. The driving signals of two adjacent scan lines among the said scan lines have a first waveform and a second waveform, respectively. The first waveform switches among a first turn-off level, a turn-on level and a second turn-off level in sequence. The second waveform switches among the second turn-off level, the turn-off level and the first turn-off level in sequence.

These and other objectives of the present invention will no doubt become obvious to those of ordinary skill in the art after reading the following detailed description of the preferred embodiment that is illustrated in the various figures and drawings.

BRIEF DESCRIPTION OF THE DRAWINGS

FIG. 1 is a schematic diagram of a pixel of a liquid crystal display (LCD) device according to an embodiment of the present invention.

FIG. 2 is a circuit diagram of an LCD device according to an embodiment of the present invention.

FIG. 3 is a timing diagram of the LCD device in FIG. 2.

FIG. 4 is a schematic diagram of an equivalent circuit of a sub-pixel in FIG. 2 when a transistor of the sub-pixel turns off.

DETAILED DESCRIPTION

Please refer to FIG. 1, which is a schematic diagram of a pixel 10 of a liquid crystal display (LCD) device according to an embodiment of the present invention. To improve color washout effect, the pixel 10 is composed of sub-pixels Pix1 and Pix2. Each of sub-pixels Pix1 and Pix2 include liquid crystal capacitors Clc1 and Clc2, storage capacitors Cs1 and Cs2, switches SW1 and SW2, respectively. The switches SW1 and SW2 are Thin Film Transistors (TFTs). The source electrode of the switch SW1 is electrically connected to a data line Dk. The drain electrode of the switch SW1 is electrically connected to one terminal of the liquid crystal capacitor Clc1 and one terminal of the storage capacitor Cs1. The gate electrode of the switch SW1 is electrically connected to a scan line Gk. The source electrode of the switch SW2 is electrically connected to the data line Dk. The drain electrode of the switch SW2 is electrically connected to one terminal of the liquid crystal capacitor Clc2 and one terminal of the storage capacitor Cs2. The gate electrode of the switch SW2 is electrically connected to the scan line Gk. Besides, the other terminal of the storage capacitor Cs1 is electrically connected

to a scan line $G(k+1)$. The other terminal of the storage capacitor $Cs1$ is electrically connected to a scan line $G(k+2)$. The other terminals of the liquid crystal capacitors $Clc1$ and $Clc2$ are electrically connected to a common voltage $Vcom$. The scan lines $G(k+1)$ and $G(k+2)$ are a next scan line of the scan line Gk and a next two scan line of the scan line Gk , respectively.

Therefore, by driving signals of the scan lines $G(k+1)$ and $G(k+2)$, voltages of the storage capacitors $Cs1$ and $Cs2$ can be modulated to make driving voltages of the sub-pixels $Pix1$ and $Pix2$ different, and thereby the color washout effect can be improved.

Please continue referring to FIG. 2, which is a circuit diagram of an LCD device **20** according to an embodiment of the present invention. As shown in FIG. 2, the LCD device **20** includes pixels $P11-Pmn$, data lines $D1-Dn$, scan lines $G1-G(m+2)$ and a gate driving circuit **21**. The pixels $P11-Pmn$ are implemented by the pixel **10** shown in FIG. 1, and formed at the intersection of each data line and each scan line. Each pixel is connected in the way as mentioned above, and thus not narrated herein. The gate driving circuit **21** is electrically connected to the scan lines $G1-G(m+2)$, and used for generating driving signals of the scan lines $G1-G(m+2)$ in sequence in order to drive the transistor switches on the scan lines $G1-G(m+2)$. Thus, if the resolution of the LCD device **20** is n by m , the present invention only needs to add the two scan lines $G(m+1)$ and $G(m+2)$ on the LCD panel, such that the voltages of the storage capacitors can be modulated by the driving signals of the scan lines to make the driving voltages of the two sub-pixels different, and that the color washout effect can be improved.

Consequently, the present invention needs neither an extra circuit for generating modulation signals of the storage capacitors, nor extra layouts on the panel. Therefore, the aperture ratio of the LCD device is not affected. Regarding the detail operations of the LCD device **20**, please continue referring to the following statements.

According to an embodiment of the present invention, driving signals of two adjacent scan lines have a first waveform and a second waveform, respectively. The first waveform switches among a first turn-off level $Vgl1$, a turn-on level Vgh , and a second turn-off level $Vgl2$ in sequence. The second waveform switches among the second turn-off level $Vgl2$, the turn-on level Vgh , and the first turn-off level in sequence. Compared with driving signals of the conventional scan lines which have only two voltage levels, the driving signal of the present invention takes advantage of one voltage level for turning on the transistor but two voltage levels for turning off the transistor. Besides, the driving signals of two adjacent scan lines have different waveforms.

Please refer to FIG. 3, which is a timing diagram of the LCD device **20** in FIG. 2. As shown in FIG. 3, if the driving signal of the scan line $G1$ has the first waveform and switches among the first turn-off level $Vgl1$, the turn-on level Vgh , and the second turn-off level $Vgl2$, the driving signals of the scan line $G2$ and the scan line $G3$ would have the second waveform and the first waveform, respectively. To take the pixel $P11$ as an example, when the driving signal of the scan line $G1$ switches from the first turn-off level $Vgl1$ to the turn-on level Vgh , the transistors of the two sub-pixels both turn on at the same time to allow the driving signal of the data line $D1$ to charge the storage capacitor and the liquid crystal capacitor, and thereby generate two identical sub-pixel driving voltages $Vd1$ and $Vd2$. When the driving signal of the scan line $G1$ switches from the turn-on level Vgh to the second turn-off level $Vgl2$, the transistors of the two sub-pixels both turn off at the same time, such that the driving voltages $Vd1$ and $Vd2$

are both kept in a floating state. In this situation, when the driving voltages of the scan lines $G2$ and $G3$ vary, for example, the driving voltage of the scan line $G2$ switches from the first turn-off level $Vgl1$ to the second turn-off level $Vgl2$, and the driving voltage of the scan line $G3$ switches from the first turn-off level $Vgl1$ to the second turn-off level $Vgl2$, the sub-pixel driving voltages $Vd1$ and $Vd2$ would have different voltage levels since the storage capacitors are disturbed.

10 Please refer to FIG. 4, which is a schematic diagram of an equivalent circuit of a sub-pixel **40** in FIG. 2 when a transistor of the sub-pixel **40** turns off. According to Charge Conservation theory, when the driving signal of the scan line Gk switches from the first turn-off level $Vgl1$ to the second turn-off level $Vgl2$, a variance ΔV of the sub-pixel driving voltage Vd can be expressed by: $\Delta V = (Vgl2 - Vgl1) \times (Cs / (Cs + Clc))$. Namely, the variance ΔV of the sub-pixel driving voltage Vd is a result of charge sharing performed by the storage capacitor Cs and the liquid crystal capacitor Clc on the voltage difference between the first turn-off level $Vgl1$ and the second turn-off level $Vgl2$.

Thus, please continue referring FIG. 3, when the driving signals of the scan lines $G2$ and $G3$ vary, the two sub-pixel driving voltages $Vd1$ and $Vd2$ can be expressed by:

$$Vd1 = Vdp - \Delta Vp + \Delta V$$

$$Vd2 = Vdp - \Delta Vp - \Delta V$$

Where, Vdp is a positive polarity voltage given by the scan line $D1$ when the transistor turns on; ΔVp is a voltage drop caused by coupling of a gate-drain capacitance (Cgd) when the transistor turns off. This is known by those skilled in the art, and thus not narrated herein. As a result, the sub-pixel driving voltages $Vd1$ and $Vd2$ could have different voltage levels through variation of the driving voltages of the scan lines $G2$ and $G3$.

40 In this situation, the gate driving circuit **21** of the present invention can further change magnitudes of the variance ΔV of the sub-pixel driving voltages by adjusting the voltage levels of the first turn-off level $Vgl1$ and the second turn-off level $Vgl2$, so as to optimize the characteristics of the LCD device according to different extents of the color washout effect. Such derivative embodiment is also included in the field of the present invention.

On the other hand, to meet the requirement of polarity inversion operation, the driving signal of each scan lines has different waveforms in two successively frames. As shown in 50 FIG. 3, since the driving signals of the scan lines $G2$ and $G3$ have different waveforms in two successive the frame_1 and the frame_2, respectively, the sub-pixel driving voltages $Vd1$ and $Vd2$ in the frame_2 can thus be expressed by:

$$Vd1 = Vdn - \Delta Vp - \Delta V$$

$$Vd2 = Vdn - \Delta Vp + \Delta V$$

Where, Vdn is a negative polarity voltage given by the scan line $D1$ when the transistor turns on; ΔVp is a voltage drop caused by coupling of the gate-drain capacitance (Cgd) when the transistor turns off. In this situation, assuming that the positive polarity voltage Vdp is equal to the negative polarity voltage Vdn , voltages across the liquid crystal capacitors $Clc1$ and $Clc2$ are identical in two successive frames for two sub-pixels of the pixel $P11$, and thus no DC level variance remains.

More precisely, since the common voltage V_{com} is given by: $V_{com} = (V_{dp} + V_{dn})/2 - \Delta V_p$, the voltages across the liquid crystal capacitors Clc_1 and Clc_2 in the frame_1 can be expressed by:

$$\Delta V_{clc1} = V_{d1} - V_{com} = V_{dp}/2 - V_{dn}/2 + \Delta V,$$

$\Delta V_{clc2} = V_{d2} - V_{com} = V_{dp}/2 - V_{dn}/2 - \Delta V$, respectively. Similarly, the voltages across the liquid crystal capacitors Clc_1 and Clc_2 in the frame_2 can be expressed by:

$$\Delta V_{clc1} = V_{d1} - V_{com} = |V_{dp}/2 - V_{dn}/2 + \Delta V|,$$

$$\Delta V_{clc2} = V_{d2} - V_{com} = |V_{dp}/2 - V_{dn}/2 - \Delta V|, \text{ respectively.}$$

Therefore, the voltages across the liquid crystal capacitors Clc_1 and Clc_2 are identical in two successive frames, and thus no DC level variance exists, as shown in FIG. 3.

Conclusively, the LCD device of the present invention couples the storage capacitors of the two sub-pixels to the next scan line and the next two scan line, respectively, and thus the driving voltages of the two sub-pixels can be modulated by the driving signals of the scan lines, so as to improve the color washout effect caused by the side viewing angle. Consequently, the present invention needs neither the extra circuit for generating the modulation signals of the storage capacitor, nor extra layouts on the LCD panel. Thus, there will not be any impact on the aperture ratio of the LCD device.

Those skilled in the art will readily observe that numerous modifications and alterations of the device and method may be made while retaining the teachings of the invention.

What is claimed is:

1. A liquid crystal display (LCD) device for improving color washout effect, the LCD device comprising:
  - a first data line;
  - a first scan line;
  - a second scan line being a next scan line of the first scan line;
  - a third scan line being a next scan line of the second scan line;
  - a pixel formed at an intersection of the first data line and the first scan line, the pixel comprising:
    - a first sub-pixel comprising:
      - a first liquid crystal capacitor having a first terminal and a second terminal electrically connected to a common voltage;
      - a first storage capacitor having a first terminal and a second terminal electrically connected to the second scan line; and
      - a first switch having a first terminal electrically connected to the first data line, a second terminal electrically connected to the first terminal of the first liquid crystal capacitor and the first terminal of the first storage capacitor, and a control terminal electrically connected to the first scan line; and
    - a second sub-pixel comprising:
      - a second liquid crystal capacitor having a first terminal and a second terminal electrically connected to the common voltage;
      - a second storage capacitor having a first terminal and a second terminal directly electrically connected to the third scan line; and

a second switch having a first terminal electrically connected to the first data line, a second terminal electrically connected to the first terminal of the second liquid crystal capacitor and the first terminal of the second storage capacitor, and a control terminal electrically connected to the first scan line; and

a gate driving circuit, electrically connected to the first scan line, the second scan line and the third scan line, for generating driving signals of the first scan line, the second scan line and the third scan line in sequence; wherein the driving signals of two adjacent scan lines among the said scan lines have a first waveform and a second waveform, respectively, the first waveform switches among a first turn-off level, a turn-on level and a second turn-off level in sequence, and the second waveform switches among the second turn-off level, the turn-on level and the first turn-off level in sequence.

2. The LCD device of claim 1, wherein the first switch and the second switch are conducted for allowing signals of the first data line being transmitted to the first sub-pixel and the second sub-pixel to generate a driving voltage of the first sub-pixel and a driving voltage of the second sub-pixel when the driving signal of the first scan line switches to the turn-on level.

3. The LCD device of claim 2, wherein the first switch and the second switch are turned off when the driving signal of the first scan line switches to the first turn-off level or the second turn-off level, and the driving voltage of the first sub-pixel and the driving voltage of the second sub-pixel are modulated by the driving signal of the second scan line and the driving signal of the third scan line, respectively, after the first switch and the second switch are turned off.

4. The LCD device of claim 3, wherein a voltage variance in the driving voltage of the first sub-pixel is a result of charge sharing performed by the first storage capacitor and the first liquid crystal capacitor on a voltage difference between the first turn-off level and the second turn-off level.

5. The LCD device of claim 3, wherein a voltage variance in the driving voltage of the second sub-pixel is a result of charge sharing performed by the second storage capacitor and the second liquid crystal capacitor on a voltage difference between the first turn-off level and the second turn-off level.

6. The LCD device of claim 3, wherein the driving voltage of the first sub-pixel and the driving voltage of the second sub-pixel have voltage variances with equal magnitudes but opposite directions.

7. The LCD device of claim 1, wherein driving voltages of the first sub-pixel and the second sub-pixel have reverse polarity in two successive frames.

8. The LCD device of claim 7, wherein the driving signal of each of the said scan lines has different waveforms in two successive frames.

9. The LCD device of claim 1, wherein the first switch and the second switch are Thin Film Transistors (TFTs).
